BLOWPIPE AND METHOD OF FORMING
COMBUSTIBLE MIXTURESWilgot J. Jacobsson, Buffalo, N. Y., assignor, by
mesne assignments, to Union Carbide and Car-
bon Corporation, a corporation of New York

Application September 13, 1933, Serial No. 689,176

19 Claims. (Cl. 158—27.4)

This invention relates to improvements in blowpipes, such as are used in performing welding, cutting and similar operations on metal, and also to a method of forming combustible gas mixtures of air, oxygen and a fuel gas.

Heretofore, the combustible mixture usually formed in the blowpipe contained substantially pure oxygen and a fuel gas. Generally the mixture formed within the blowpipe contained about one-half of the oxygen required to combine with the fuel gas and the remainder of the oxygen required to complete the combustion of the fuel gas was taken from the air surrounding the flame. Such combustible mixtures produce a flame generally known as a neutral flame. A given fuel gas in such a mixture produces a fixed flame temperature at its hottest portion, the portion of the flame that is generally applied to metals or the like for heating them. It is this portion of the flame that is referred to where flame temperature is mentioned herein. In the use of fuel gases such as acetylene which produce relatively high temperature flames due to a high heat of combustion, it is desirable to reduce the flame temperature to make the flame suitable for welding and/or cutting operations which require relatively low flame temperature, such as may be produced with hydrogen.

Furthermore, in the type of blowpipe used heretofore where a large portion of the oxygen is absorbed from the air from without the blowpipe, the fuel gas is not burned as efficiently as when a greater portion of the oxygen is mixed with the fuel gas within the blowpipe.

Where attempts have been made to increase the burning efficiency of the fuel gas by increasing the ratio of the oxygen to the fuel gas above the normal ratio in the blowpipe, objectionable characteristics of the flame have been produced. Some of these objectionable characteristics are shown by the lack of stability of the flame, the occurrence of flashbacks, the oxidizing effect of the flame on welded metal and excessive heating of the metal in some welding and cutting operations.

Therefore, an object of this invention is to provide an improved apparatus and method for utilizing a fuel gas having a high heat of combustion, such as acetylene, for producing stable flames having a higher or lower temperature than the neutral flames and having a high resistance to flashbacks.

Another object of this invention is to reduce the consumption of fuel gas and to stabilize the flame.

A further object of this invention is to produce a flame adapted to cause the formation of a less adherent slag when used in combination with an oxygen stream especially for use in deseaming or flame machining operations.

The above and other objects and the novel features of this invention will be apparent from the following description and the accompanying drawings, in which

Fig. I is a top plan view of a blowpipe embodying this invention; 10

Fig. II is a rear end view of the blowpipe shown in Fig. I.

Fig. III is a cross section on line III—III in Fig. I. 15

Fig. IV is a cross section on line IV—IV in Fig. VIII showing the valves in the blowpipe rear body and having the mixer nozzles removed from the body.

Figs. V, VI, and VII are respectively cross sectional views of the rear body of the blowpipe shown on lines V—V, VI—VI and VII—VII of Fig. II. 20

Fig. VIII is a fragmentary bottom view of the blowpipe rear body with the gas control valves removed and Fig. IX is a rear view of the blowpipe rear body on line IX—IX of Fig. III showing the hose line connections and gas control valves removed. 25

Fig. X is a cross section of the blowpipe on line X—X in Fig. III, showing the blowpipe head.

Fig. XI is a diagrammatic sketch of the blowpipe.

Most of the principles involved in the method and apparatus described herein are applicable to both cutting and welding blowpipes. For the purpose of illustrating this invention, the method and apparatus are described in reference to a cutting blowpipe using a low velocity oxygen jet adapted for removing the surface metal. Such operations are known as deseaming or flame machining.

The blowpipe comprises a handle H to which a valve body B is attached. Hose lines (not shown) for fuel gas and a combustion supporting gas such as oxygen are connected to the valve body B. The oxygen for cutting purposes is fed to the blowpipe head H^c and controlled by a cutting oxygen valve V in the usual manner. Air is mixed with a portion of the oxygen supplied to the blowpipe and then a fuel gas is mixed with the air and oxygen mixture to produce a combustible gas mixture suitable for producing a heating flame. The oxygen and fuel gas employed to produce the combustible gas mixture may be turned on 55

and off by a pair of valves operated by a common lever which unit is called herein a gas saver S. The mixture discharged from the blowpipe head H^o is ignited by a continuously burning flame which is produced by a fuel gas discharged from a pilot light burner P.

10 A hose (not shown) for supplying oxygen under pressure to the blowpipe may be attached to a hose nipple 15 which is connected to a pipe fitting 16 by a union nut 16. The pipe fitting 16 is screwed into a valve chamber 17 formed in the valve body B which receives the oxygen from the fitting 16. The cutting oxygen is controlled by the cutting oxygen valve V having a seat 18 held 15 in place by an externally threaded locking ring 19 screwed into the valve chamber up against the valve seat. A valve stem bushing 20 is threaded into the end of the valve chamber 17 on the outlet side 21. A central bore 22 is formed in the bushing 20 through which the valve stem 23 passes. A packing nut 24 receives the stem 23 and is screwed on the bushing 20. The valve V is retained on its seat 18 by means of a valve spring 25 which is compressed between the pipe 20 fitting 16 and a valve spider 26 which centers the valve in the chamber. The cutting oxygen valve V may be operated by means of a lever 27 which is actuated by an externally extending button 28. The lever 27 is pivoted on a pin 29 in a block 30 30 in the blowpipe handle H. The lever 27 actuates a plunger 31 which in turn actuates the valve stem 23 and the cutting oxygen valve V.

Upon pressing the cutting oxygen valve button 28, the oxygen passes through the valve seat 18 and into the outlet 21 of the valve chamber 17. As shown in Fig. VII a transverse bore 32 conducts the cutting oxygen from the valve outlet 21 to a longitudinal bore 33 in the valve body B to which a tube 34 is connected which conducts the oxygen to the blowpipe head H^e. The cutting oxygen tube 34 is soldered or otherwise connected to a bore 35 in the blowpipe head. The bore 35 in the head H^e is pierced by a transverse threaded bore 36 into which a constricting plug 37 is threaded. Plugs of different dimensions may be interchanged with each other to secure the passage of the desired volume of oxygen to the blowpipe nozzle 38. The nozzle 38 is held in a cavity 39 in the head H^e by means of a nozzle nut 40. The nozzle 38 is provided with a central bore 41 which communicates with the cavity 39 in the head H^e and conducts the oxygen to the discharge orifice 42 in the nozzle 38.

The heating or preheating oxygen to be combined with the fuel gas to form the combustible gas mixture is taken from the inlet to the cutting oxygen valve 17 in the valve block B through a transverse bore 43 controlled by a stop valve 44 located therein which is operated by a valve knob 44 as shown in Fig. IV. The oxygen may pass through the valve seat 45 to a passage 46 leading to the inlet 47 of the oxygen valve 48 in the gas saver S. When the gas saver valve 48 is opened by a mechanism hereinafter described the oxygen may pass from the inlet 47 of the valve to the outlet 49 of the valve and then to a passage 50 leading to an air oxygen mixer 51 for mixing air with the oxygen as shown in Figs. IV and VI. The oxygen enters the bore 52 in the air-oxygen mixer 51 which is closed by a screw plug 53 threaded into the end of the mixer bore. The oxygen passes through an injector nozzle 54 which is retained in the bore 52 by means of an externally threaded locking ring 55. As the oxygen passes through the discharge orifice of the

nozzle 54, air is drawn or aspirated into the oxygen stream from an annular chamber 57 around the nozzle, which is supplied with air from the atmosphere by means of a bore 56. The entrance of air bore 56 is protected by a shield 58 which may be made in the form of a meshed screen to prevent the bore from being plugged with dirt or by the operator's hand. Clearly the rate at which air is aspirated by the oxygen which the injector nozzle 54 projects will be substantially proportional to the rate of oxygen projection. Since the oxygen valve 48 of the gas saver valve arrangement is either fully opened or entirely closed it follows that the stop valve 44 controls the rate of flow of the air-oxygen mixture and provides in one form means for keeping constant the rate of flow of the air-oxygen mixture. The mixture of air and oxygen is conducted through a throat 59 to a tube 60 which is connected to said throat. The air-oxygen tube 60 extends to the head H^e of the blowpipe and is connected to a chamber therein including a transverse bore 61 in the blowpipe head. A return tube 62 for the air and oxygen is connected at one end to the transverse bore 61 in the blowpipe head H^e and at the other end to a bore 63 in the valve body B as shown in Fig. V. The bore 63 and a transverse bore 63^a connect the return tube 62 to the rear end of the bore 64 of a mixer 65 for mixing a fuel gas with the air and oxygen. The rear end of bore 64 of the air-oxygen-fuel gas mixer 65 is closed by a threaded plug 66 screwed into the outer end of the mixer bore. A mixer nozzle 67 is secured in the mixer bore 64 by means of an externally threaded locking ring 68.

The fuel gas to be mixed with the air and oxygen in the air-oxygen-fuel gas mixer 65 is conducted to the blowpipe through a hose (not shown) which may be connected to a hose nipple 69, secured to a fuel gas control valve body 70 by means of a union nut 71. A passage 70^a extends through the fuel gas valve body 70 and a valve 72 operated by a knob 72^a is located therein to control the flow of the gas from the valve inlet 70^b to its outlet 70^c. The valve body 70 is screwed into a bore 73 in the valve body B attached to the rear end of the handle H so that the valve outlet 70^c is connected to a chamber 73^a in the valve body B. A passage 74 in the valve body B connects the chamber 73^a to the inlet chamber 15 of the fuel gas valve 76 of the gas saver S. A metering plug 77 is screwed into the outlet from the valve 76 and the plug 77 is provided with a central bore which delivers the fuel gas to a passage 78 leading to the air-oxygen-fuel gas mixer 65. Different metering plugs may be made with bores of different size and they may be made interchangeable with each other to secure the desired proportion of fuel gas in the combustible mixture as will be hereinafter explained. When the gas saver valves 48 and 76 are open the mixture of air and oxygen is discharged through the air-oxygen-fuel gas mixer nozzle 67 and mixes with the fuel gas at the end of the nozzle. Preferably the air-oxygen-mixture is given a greater velocity than the fuel gas to suck the fuel gas into the air-oxygen stream. The combustible mixture formed by the mixing of the air and oxygen and the fuel gas are conducted to a chamber 79 in the head H^c of the blowpipe by means of a tube 80 which is connected at one end to the expansion chamber 81 leading from the throat 82 of the air-oxygen-fuel gas mixer 65 and at the other end to the blowpipe head H^c. The combustible mixture passes through longitudinal gas

mixture passages 80 in the blowpipe nozzle 38 and may be ignited at the discharge end of the nozzle by means of the pilot light burner P, which will be hereinafter described.

The length and volume of the conduit 60, 62 between the air-oxygen mixer 51 and the air-oxygen-fuel gas mixer 65 is constructed in accordance with the principles set forth in my copending application Serial No. 631,288, filed August 31, 1932, entitled Blowpipes and a method of preventing flashbacks therein. Briefly, the section of the heating oxygen tube between the end of the injector nozzle 54 of the air-oxygen mixer 51 and the end of the nozzle 67 of air-oxygen-fuel gas mixer 65 is constructed to permit the free passage of gases from the mixer throat 82 of the latter mixer backward into said section of the heating oxygen tube when a backfire occurs in the mixing tube 80. For the purpose of preventing flashbacks, a minimum length and volume of this section of the heating oxygen tube for a given length and volume of the mixing tube 80, 81, 82, 90 extending from the end of the air-oxygen-fuel gas mixer nozzle 67 to the end of the main burner nozzle 38 is required. Within limits, the minimum length and volume of the section of the heating oxygen tube varies inversely as the length and volume of the mixing tube. The air-oxygen-mixer 51 is placed at such a point in the heating oxygen tube that the backfiring gases that may be forced backward into this tube will be completely burned out or extinguished before reaching the mixer 51 and thus prevent any flame from escaping through the air inlet 56.

The gas saver valves 48 and 76 are of the diaphragm type and they are secured into cavities 91 in the rear valve body B by means of hollow nuts 92 which are screwed into the cavities 91. The nuts 92 clamp the diaphragm valves 48 and 76 between the end of the nuts 92 and the bottom of the cavities 91. The diaphragm valves 48 and 76 are normally retained on their seats 93 by means of springs 94 compressed between the outer end of the hollow nuts 92 and a shoulder on the valve stems 95 of each of the diaphragm valves 48 and 76. Each of the valve stems 95 is attached at one end to its corresponding valve and the other end of each stem extends through its corresponding hollow nut 92. The gas saver valves 48 and 76 are operated by means of a single lever 96 which is pivoted on a pin 97 mounted in arms 98 on the valve body B. The outer ends of the valve stems 95 are provided with necks 99. The rear arm 96 of the gas saver lever 96 fits around the necks 99 and is adapted to contact with the stem heads 100 at the outer end of the necks 99 to operate the valves 48 and 76 in opposition to the springs 94. The gas saver lever 96 is cut away next to head 100 of the stem of the fuel gas valve 76 so that the lever will strike the head 100 of the oxygen valve 48 before it strikes the head 100 of the fuel gas valve 76 and thereby cause the oxygen valve 48 to open sooner than and close later than the fuel gas valve 76. This construction of the gas saver S turns the oxygen on before the fuel gas is turned on and thereby creates a suction in the air-oxygen-fuel gas mixer 65 before the fuel gas reaches that point and thereby prevents the fuel gas from escaping through the air inlet 56 in the air-oxygen mixer or being mixed with the air and oxygen at a point in rear of the mixer nozzle 67.

The pilot light burner P is supplied with fuel gas through a passage 101 in the rear valve body B, which branches off from the passage 14 leading to the fuel gas saver valve 76 as shown in

Figs. V and VIII. A tube 102 is connected at one end to the end of the passage 101 in the valve body B and at the other end to a bracket 103 which supports pilot light burner P. The bracket 103 is secured to the combustible mixture tube 80 near the blowpipe head H by means of clamping bolts 104.

The bracket 103 is provided with a bore 105 which is connected to the pilot light fuel gas tube 102. The neck 106 around the orifice of the bore 105 in the bracket is threaded and the burner P is screwed to the bracket at this point. The inlet coupling 107 of the burner is provided with a double screen 108 to clean the fuel gas and prevent the burner nozzle 109 from being clogged. The screen 108 is retained in the bore of the burner by means of an externally threaded locking ring 110. The fuel gas passes from the screen chamber 111 through a metering orifice 112 which determines the quantity of fuel gas to be consumed by the pilot burner. The outlet from the metering orifice 112 is internally threaded and the pilot burner nozzle 109 is threaded into the outlet. The pilot flame is protected by a shield 113 which surrounds the pilot burner nozzle.

The blowpipe is placed in operation by connecting the hose nipple 15 to a source of supply of oxygen under a suitable pressure and by connecting the hose nipple 69 to a source of supply of fuel gas under a suitable pressure, all of the blowpipe valves being closed. The fuel gas stop valve 72 is then fully opened and the heating oxygen valve 44 is slightly opened. Fuel gas will then flow directly to the pilot light burner P and is lighted at the nozzle 109. The pressure of the fuel gas in the hose line and the size of the orifices in the pilot light burner P are so proportioned in respect to each other that a flame of sufficient length is produced at the end of the pilot light nozzle P to ignite the combustible mixture which is later caused to issue from the blowpipe nozzle 38.

The gas saver lever 96 is then drawn toward the handle H with the fingers of the hand which grips the handle. The fuel gas issues through the fuel gas valve 76 of the gas saver S and the heating oxygen issues through the oxygen valve 48 of the gas saver S. The oxygen and the fuel gas mix at the mixer 65. The mixture flows to the blowpipe nozzle 38 and is ignited by the pilot flame of the pilot light burner P. The flow of the heating oxygen is then adjusted by operating the heating oxygen valve knob 44. The oxygen valve 48 of the gas saver S being open, the oxygen flows through this valve to the air-oxygen injector mixer 51 and draws in the desired quantity of air through the air inlet. The mixture of air and oxygen flows through a conduit 60, 62 to the air-oxygen-fuel gas mixer 65 where it mixes with the fuel gas to obtain a flame having characteristics which the combination of parts and construction of the blowpipe are designed to produce when using a selected type of fuel gas. Since the fuel gas metering plug 71 fixes the flow of the fuel gas for a given pressure in the fuel gas hose line, the flame of the proper characteristics is obtained by adjusting the heating oxygen valve 44 only.

When the torch is used for cutting metal, or the like, the cutting oxygen is turned on by pressing the button 28 which may be done with the thumb of the hand which at the same time grips the gas saver lever 96 and the handle H.

The type of flame for which the blowpipe is

designed is obtained by regulating the heating oxygen valve only as the quantity of fuel gas permitted to flow into the mixture is fixed by the orifice in the metering plug 71. Due to this arrangement, when the flame attains the proper length and stability the combustible mixture will then contain the proportions of air, oxygen and fuel gas the blowpipe may be designed to produce. These proportions, however, may be varied to 10 produce a flame having characteristics suitable for different operations. The change in the mixture may be effected by throttling the air drawn into the air-oxygen mixture or otherwise changing the construction of the air-oxygen mixer, as by substituting one mixer for another, so that the air and oxygen may be mixed in different proportions. The orifice in the metering plug 71 in the fuel gas passage may also be changed to 15 effect a change in the proportion of fuel gas in the combustible mixture.

In welding certain kinds of metals it is desirable to use low flame temperatures to prevent the metal from being burned. To accomplish this purpose the ratio of air to the remainder of the 25 mixture is increased. The lowering of the flame temperature by the addition of air is especially useful as it makes possible the employment of a fuel gas having a high heat of combustion to produce either high or low temperature flames 30 and thereby obviates the necessity of having two kinds of fuel gas available.

The addition of air to the combustible mixture within the blowpipe as compared to the absorption of oxygen from the air without the blowpipe 35 effects an economy in the consumption of the fuel gas. In view of this feature it is also advantageous to add air to the combustible mixture and use a relatively high ratio of oxygen to the fuel gas in order to maintain the flame temperature the same as, or even higher than, that of a normal neutral flame having no air added to the mixture within the blowpipe.

Air in a combustible mixture containing a given ratio of oxygen to fuel gas decreases the rate of 45 flame propagation when the mixture is ignited, and thereby renders the flame more stable and less subject to backfires. The air in the combustible mixture is especially advantageous as the oxygen content of the mixture becomes greater 50 than that of a mixture yielding a neutral flame since an increase of the oxygen content normally increases flame propagation and decreases the stability of the flame.

The increase in the ratio of oxygen to the fuel 55 gas in a mixture for the purpose of increasing the flame temperature and the addition of air to a mixture within the blowpipe for the purpose of economizing on fuel gas and stabilizing the flame is especially advantageous in descaling or flame 60 machining operations, in which operations the flame is used in combination with a low velocity oxygen cutting stream to remove surface metal. Preferably acetylene is used as the fuel gas in the mixture. The oxygen content of a mixture containing air, oxygen and acetylene may be increased to decrease the time required to preheat the metal to start the cut and the air in the mixture will maintain the flame in a stable condition. In addition to the decrease in the preheat time 65 that may be effected by the air-oxygen-acetylene mixture the oxidized metallic slag removed from the cut by the joint action of the flame and the oxygen stream is less adherent than slags produced by flames having no air added to the mixture within the blowpipe.

The air-oxygen-fuel gas flames also may be used for preheating metals for cutting with high velocity oxygen. The temperature of the flame may be made suitable for the particular class of metal or cut by controlling the proportions of the 5 air, oxygen and fuel gas mixed within the blowpipe.

I claim:

1. A blowpipe comprising inlet conduits for air, oxygen and a fuel gas; an injector connected to 10 said air and oxygen inlets for aspirating air into the oxygen; and an air-oxygen-fuel gas mixer independently connected to the outlet from said injector and to said fuel gas inlet for mixing the mixture of air and oxygen with a fuel gas. 15

2. A blowpipe comprising an injector for mixing air with oxygen; said injector having a mixing chamber in open communication with the atmosphere; an injector nozzle adapted to be connected to oxygen under pressure and to aspirate air into said mixing chamber; a mixer for mixing the mixture of air and oxygen with a fuel gas; said mixer having a mixing chamber and a nozzle extending to said chamber; said second mixing chamber and associated nozzle being connected one to a fuel gas supply and the other to the outlet from the air and oxygen mixing chamber. 20 25

3. A blowpipe comprising inlet conduits for air, oxygen and a fuel gas; an injector for mixing air with oxygen; said injector comprising a nozzle having a central passage connected to 30 said oxygen inlet; an air chamber connected to said air inlet and adapted to have air aspirated therefrom by said nozzle; an air-oxygen-fuel gas 35 mixer connected with the outlet from the said injector; and independent means connecting the said mixer with the said fuel gas inlet conduit.

4. A blowpipe comprising an inlet conduit for air under atmospheric pressure; a shield for protecting said air inlet; inlet conduits for oxygen and a fuel gas under pressure higher than atmospheric pressure; an injector connected to said air and oxygen conduits and being adapted to aspirate air into the outlet of said injector from said 40 air-conduit; and an air-oxygen-fuel gas mixer independently connected to the outlet of said injector and to said fuel gas conduit. 45

5. A blowpipe comprising an inlet conduit for air under atmospheric pressure; inlet conduits 50 for oxygen and a fuel gas under pressure higher than atmospheric pressure; an injector connected to said air and oxygen conduits and being adapted to aspirate air into the outlet of said injector from said air conduit; an air-oxygen-fuel gas mixer connected to said fuel gas conduit; and a conduit connecting the outlet of said injector to said mixer, said latter conduit being of sufficient length to prevent flashbacks at said mixer and back-fires through said air inlet. 60

6. A blowpipe comprising inlet conduits for air, oxygen and a fuel gas; a mixer for mixing air and oxygen connected to said air and oxygen conduits; a second mixer for mixing said mixture of air and oxygen with a fuel gas; said second mixer being connected to the outlet from 65 said first mixer and to said inlet conduit for fuel gas; and a fuel gas metering orifice in said fuel gas conduit adapted to determine the ratio of acetylene to the oxygen and air mixture for a 70 given pressure in the fuel gas conduit.

7. A blowpipe comprising an injector having an inlet for oxygen and an inlet for air; said injector being adapted to aspirate air into the oxygen stream by means of the oxygen velocity; 75

an air-oxygen-fuel gas mixer connected to the outlet of said injector and to a fuel gas conduit; a metering orifice in said fuel gas conduit; a normally closed valve in said oxygen inlet; a normally closed valve in said fuel gas conduit and a common means for operating said valves.

8. A blowpipe comprising an injector having an inlet for oxygen and an inlet for air; said injector being adapted to aspirate air into the oxygen stream by means of the oxygen velocity; an air-oxygen-fuel gas mixer connected to the outlet of said injector and to a fuel gas conduit; a metering orifice in said fuel gas conduit; a normally closed valve in said oxygen inlet; a normally closed valve in said fuel gas conduit and a common means for operating said valves, including means for opening said oxygen valve prior to the opening of said fuel gas valve, and closing said fuel gas valve prior to the closing of said oxygen valve.

9. A blowpipe comprising a handle; an air-oxygen mixer located on said handle; said mixer having an inlet for air and an inlet for oxygen; an air-oxygen-fuel gas mixer located on said handle; said air-oxygen-fuel gas mixer having an inlet for a mixture of air and oxygen and an inlet for a fuel gas; a blowpipe head; and a conduit extending from said air-oxygen mixer to said blowpipe head and returning to said inlet for the mixture of air and oxygen in said air-oxygen-fuel gas mixer.

10. A blowpipe comprising a handle; a valve body attached directly to said handle; said valve body having inlets for air, oxygen and a fuel gas; an injector in said body connected to said oxygen inlet and to said air inlet; said injector being adapted to aspirate air from said air inlet by means of the oxygen flow and mix said gases in the outlet from said injector; an air-oxygen-fuel gas mixer in said valve body for mixing said mixture of air and oxygen with fuel gas; said mixer being connected to said fuel gas inlet; a blowpipe head spaced from said valve body; a conduit extending from said outlet of said injector to said head and returning to said valve body to provide a gas passage between said injector and said mixer.

11. In a blowpipe, a source of fuel gas, a source of oxygen, an injector connected with said source of oxygen and with an air bore in said blowpipe for mixing air with the oxygen by means of such oxygen, a conduit for the oxygen-air mixture, and a second injector in said conduit connected with said source of fuel gas for mixing the oxygen-air mixture with said fuel gas to form a combustible mixture.

12. In a blowpipe, a source of fuel gas, a source of oxygen, an injector connected with said source of oxygen and with an air bore in said blowpipe for mixing air with the oxygen by means of such oxygen, a conduit for the oxygen-air mixture, and a second injector in said conduit connected with said source of fuel gas for mixing the oxygen-air mixture with said fuel gas to form a combustible mixture, said conduit being elongated between said injectors to prevent flashbacks.

13. In a blowpipe, a handle, a blowpipe head spaced from said handle, a fuel gas inlet and an oxygen inlet both in said handle, an injector in

said handle for mixing oxygen and air, said injector being in communication with atmosphere and being supplied with oxygen from said oxygen inlet, a second injector in said handle for mixing the oxygen-air mixture with fuel gas, said second injector being connected with said fuel gas inlet, and a conduit connecting the discharge end of said first-named injector with the intake end of said second-named injector, said conduit extending from said handle toward said blowpipe head and back to said handle, thereby providing a long conduit for preventing flashbacks.

14. A blowpipe comprising inlet conduits for air, oxygen and a fuel gas; a mixer for mixing air and oxygen connected to said air and oxygen conduits; a second mixer for mixing said mixture of air and oxygen with a fuel gas; said second mixer being connected to the outlet from said first mixer and to said inlet conduit for fuel gas; means for keeping constant the rate of flow of the air-oxygen mixture; and a fuel gas metering orifice in said fuel gas conduit adapted to determine the ratio of fuel gas to the oxygen and air mixture for a given pressure in the fuel gas conduit.

15. In apparatus for forming combustible mixtures of gases, a source of fuel gas, a source of oxygen, a source of atmospheric air, an injector for mixing air with oxygen by means of oxygen, and means for subsequently mixing the air-oxygen mixture with fuel gas so as to form a combustible mixture.

16. A method of forming, and controlling the composition of, a combustible gas mixture, which comprises introducing air into a flowing stream of oxygen; regulating the quantity of air thus introduced responsive to the quantity of oxygen flowing per unit of time; introducing fuel gas into a flowing stream of the thus-formed air-oxygen mixture; and regulating the quantity of fuel gas so introduced responsive to the quantity of said air-oxygen mixture flowing per unit of time.

17. A blowpipe comprising means for introducing air into a flowing stream of oxygen, means for regulating the rate of oxygen flow and the air supply responsive thereto, and means for introducing fuel gas into the thus-formed air-oxygen stream whereby the fuel gas supply is regulated responsive to the rate of air-oxygen flow.

18. In a blowpipe, the combination of a fuel gas conduit; a combustion-supporting gas conduit including an injector device for delivering such combustion-supporting gas to be mixed with the fuel gas; means for admitting air into one of said conduits; and a second injector device in the conduit to which air is admitted adjacent the point of admission of such air.

19. In a blowpipe, the combination of a body having two chambers severally communicating with a fuel gas inlet passage and an oxygen inlet passage; an injector device removably secured in one of said chambers; means for admitting air into the chamber containing said removable injector device; and means, including an injector device in the other of said chambers, for delivering the air-gas mixture to be mixed with the other gas.

WILGOT J. JACOBSSON. 70
